UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING.

1,357,802.

Specification of Letters Patent.

Patented Nov. 2, 1920.

Application filed April 11, 1919. Serial No. 289,192.

To all whom it may concern:

Be it known that I, JOHN F. O'CONNOR, a citizen of the United States, residing at Chicago, in the county of Cook and State of Illinois, have invented a certain new and useful Improvement in Side Bearings, of which the following is a full, clear, concise, and exact description, reference being had to the accompanying drawings, forming a part of this specification.

10 This invention relates to improvements in side bearings.

15 One of the objects of the invention is to provide a simple side bearing including a bodily rolling anti-friction element and especially adapted for attachment to the body bolster of a car.

20 In the drawings forming a part of this specification, Figure 1 is a vertical, sectional view of portions of a body and a truck bolster showing my improved side bearing mounted in connection therewith, the full lines indicating the anti-friction element to show it in normal position while the dotted 25 lines show its position at the end of its movement in one direction. Fig. 2 is a vertical, sectional view taken on line 2—2 of Fig. 1.

30 In said drawings, the numeral 3 indicates the lower portion of a body bolster of a railway car and 4 a portion of the truck bolster, the two bolsters being pivoted together and spaced apart in the usual manner, which will be understood.

35 The side bearing, which is mounted between the two bolsters, comprises a base member 5, an anti-friction element 6 mounted therein, a filler block 7 and a key 8, all of which will be hereinafter more specifically described. The base member 5 is preferably a casting and is of substantially hollow rectangular shape provided with the internal chamber 9 to receive the anti-friction member and outwardly provided with the 45 lugs 10—10 by means of which it is secured to the under face of the body bolster 3 by suitable means as for instance the rivets 11—11.

50 Within the chamber 9 of the base member 5 a pair of longitudinally extended tracks or ways 12—12 are provided, the same being preferably formed upon the upper faces of the inturned flanges 13—13 in the lower walls of the base member 5. The said 55 tracks are each provided at intervals with

the upwardly projecting lugs or points 14 which are adapted to enter the similarly conformed openings 15 provided in the under face 16 of the stanchions 17—17. The said stanchions in the form of my invention illustrated in the drawings are two in number, one for either end of the anti-friction member 6. Each stanchion is provided with a perforation 18 forming a bearing for a trunnion or journal 19 with which 65 the anti-friction element 6 is provided at either end.

The said anti-friction element 6 is preferably solid and its trunnions 19 are concentrically arranged with respect to the 70 bearing face 20 of the anti-friction element 6. The bearing surface 20 is so conformed that the radius from the axis of the trunnions 19 to the uppermost point of the surface 20 when the anti-friction element is in 75 its normal position as shown by the full lines in Fig. 1 of the drawings, is substantially constant. The lower bearing face 21 of the anti-friction member, which is adapted in the operation of the anti-friction 80 member to engage the upper face 22 of the truck bolster, is concentric with the trunnions 19 and of a somewhat longer radius than that from said trunnions to the upper bearing surface 20, thus forming a counter- 85 balanced weight, as indicated at 23, so that the anti-friction element 6 will, through gravity, return to its central normal position after the release of pressure following the actuation of the element 6. The stanchions 90 17 are provided with a counterbalance at their lower ends as indicated at 24 and the under face of each of said stanchions, as indicated at 16, is preferably upon an arc struck substantially from the axis of the 95 trunnions 19.

The usual conformation of the body bolster in a railroad car is shown in Fig. 2 of the drawings in this—that the same at its ends where the side bearing is designed to 100 be attached is angular to the plane of the truck bolster. Because of this, I have provided the filler block 7 which engages against the under face of the body bolster 3 and is held in position by the flat key 8, 105 which extends through the grooves 26—26 formed in the lower face of the said filler 7 and is received at its ends through the perforations 27—27 in the side walls of the base member 5. The said key is provided with 110

the head 28 at its inner end and the perforation 29 at its outer end to receive the cotter 30 which prevents its accidental displacement. The said key also forms the 5 upper bearing plate for engagement with the upper bearing face 20 of the anti-friction element 6 and is therefore preferably made of hardened steel.

From the foregoing description, it will be 10 observed that when in normal position the anti-friction element is mounted substantially midway between the ends of the chamber 9 of the base member 5 and is supported in its position by the stanchions mounted 15 upon the tracks or ways within the base member. Upon engagement of the anti-friction member between the two bolsters, the same is actuated in a direction dependent upon the relative direction of movement 20 of the bolsters, as for instance, to the left. Upon extreme movement, the anti-friction element 6 will be carried to the position shown by the dotted lines in Fig. 1 and the stanchions will be translated from their normal 25 position shown in full lines in Fig. 1 to the position illustrated by the dotted lines appearing in said figure of the drawings. Upon release of the anti-friction element 6, gravity will return the stanchions and the 30 anti-friction element to their normal position, the stanchions being centered in their return movement by the registering openings in the under faces thereof and the lugs 14 upon the ways or tracks provided there- 35 for in the base member. The ends of the said tracks or ways are provided with the shoulders 31 extending substantially vertically of the base member and shaped as indicated at 32-32 to conform substantially 40 to the stanchions when engaged thereby and to prevent their movement beyond the combined center of gravity of the stanchions and the anti-friction member 6.

It will be apparent that the side bearing 45 illustrated in the drawings and showing an embodiment of my invention is one that can be cheaply made; that it is of simple construction; and that there inheres within it an effective arrangement to insure the return 50 of the anti-friction element 6 to its normal position under force of gravity. It will also be apparent that the invention may be embodied in other designs, and it will be understood that I contemplate and seek to 55 cover all such changes and modifications in the claims following herein.

I claim:

1. In a device of the character described, 60 the combination with a bolster, of a base member secured thereto, an anti-friction element within the base member, a filler block and a bearing plate, the filler block being mounted between the bearing plate and the bolster, the bearing plate comprising a key

extending through the base member and the 65 filler block.

2. In a device of the character described, the combination with a bolster, of a base member secured thereto, an anti-friction element 70 mounted in the base member, a filler block and a bearing plate, the filler block being mounted between the bolster and the bearing plate and being provided with a groove for the passage of the bearing plate, the said bearing plate comprising a key ex- 75 tending at its ends through the base member.

3. In an anti-friction bearing, the combination with a retaining member, of a rolling, counterbalanced anti-friction element, and counterbalanced rolling supports to 80 which said anti-friction element is journaled, said supports being in turn supported by the retaining member, the anti-friction element and the supporting elements being displaced from normal equilibrium to a position in unstable equilibrium upon actuation of the bearing in either direction from central position and adapted to return to central position under the influence of gravity upon removal of the actuating force. 85

4. In an anti-friction bearing, the combination with a retaining member adapted to be secured to the under side of a body bolster; of a rolling counter-balanced anti-friction element; and counter-balanced rolling supports separate from the anti-friction element to which the latter is pivotally attached, said retaining member having an upper bearing surface on its interior on which the upper part of the anti-friction element is adapted to roll, said retaining member having also supporting ledges for said rolling supports. 90

5. In an anti-friction bearing of the character described, the combination with a hollow substantially rectangular retaining member adapted to be secured to the under side of a body bolster of a car, said retaining member having a removable bearing surface therein near the top thereof and horizontally extending supporting ledges near the bottom thereof on its opposite side walls; of a rolling stanchion mounted on each of said ledges and adapted to rock back and forth; and an anti-friction rocker, 105 having concentric upper and lower bearing surfaces, pivotally supported on said stanchions, the upper bearing surface of the anti-friction element coöperating with said bearing surface of the retaining member and the lower bearing surface of the anti-friction element extending below the retaining member and adapted to coöperate with an opposed bearing surface. 110

In witness that I claim the foregoing I 125 have hereunto subscribed my name this 9th day of Apr., 1919.

JOHN F. O'CONNOR.
